CIGARETTE PACKAGE HOLDER

Fred J. Mallet, New York, N. Y.

Application December 22, 1945, Serial No. 636,689

1. Claim. (Cl. 312—31)

1

This invention relates to package holders. It is an object of the invention to provide a device which shall retain, in association, a package, such as a package of cigarettes, and a packet of matches. Usually, a package of cigarettes, once opened and carried in one's pocket, empties its contents into the pocket unless means are provided to prevent such an undesirable result, and to retain the cigarettes assembled with the package until they are to be consumed. Likewise, the smoker finds the usual packet of matches anywhere but in the proper place when he needs a match. In manipulating the package and the packet to light a cigarette, the smoker finds he requires free movement of both hands for all steps.

It is an object of the invention to provide a device to facilitate the manipulation of cigarette package and match packet, as, for instance, by one while driving an automobile.

Other objects of the invention will be set forth hereinafter, or will be apparent from the description and the drawings, in which are illustrated embodiments of constructions for carrying out the invention.

The invention, however, is not intended to be restricted to any particular construction or constructions, or to any particular arrangement of parts, or to any particular application of any such constructions or any such arrangement of parts, or to any specific method of operation, or to any of the various details thereof, even where specifically shown and described herein, as the same may be modified in various particulars, or may be applied in many varied relations, without departing from the spirit and scope of the claimed invention, practical constructions embodying certain details of the invention being illustrated and described, but only for the purpose of complying with the requirements of the Statutes for disclosure of operative embodiments, and without attempting to disclose all of the various forms and modifications in which the invention might be embodied.

On the drawings, in which the same reference characters refer to the same parts throughout, and in which are disclosed such practical constructions:

Fig. 1 is a perspective view of a device for retaining a cigarette package and a packet of matches in accordance with the invention;

Fig. 2 is a view, in vertical cross-section, illustrating the arrangement of the device shown in Fig. 1 in connection with an ash tray, the cigarette package being shown in elevation and a

2

piece of advertising matter being shown in cross-section;

Fig. 3 is a view in horizontal cross-section of the device shown in Fig. 1;

5. Fig. 4 is a detail of a portion of the device shown in Fig. 1, a match packet being shown disposed upon a wall, the wall and portions of the match packet being shown in cross-section;

Fig. 5 is a plan view of a piece of metal, developed and before bending, to illustrate the disposition of the various parts of the device in the blank;

10 Fig. 6 is a view similar to Fig. 3, illustrating a construction of a modified form of package holder;

Fig. 7 is a view similar to Fig. 4, illustrating a modified form of wall structure for the device, illustrating the disposition of the match packet in that relation;

20 Fig. 8 is a side elevational view of a modified form of package-holding device, the package being shown in elevation;

Fig. 9 is a view in side elevation of a device embodying features of the invention in modified form, the cigarette package being shown moved sideways partly out of association with the device;

Fig. 10 is a view in end elevation of a modified form of the device embodying certain of the features of the invention; and

Fig. 11 is a view in vertical cross-section of the device shown in Fig. 10.

In Fig. 1, is illustrated holder 10, which embodies features of the invention. Holder 10 may be formed from a single piece 12 of sheet metal; in this case, piece 12 has been bent to form a substantially U-shaped member 14, consisting of a base 16 and two upstanding walls 18 and 20. Base 16 is of such width that walls 18 and 20 are spaced from each other a distance sufficient so that a package 22 of cigarettes may be slid between the walls and then be held by a snug fit. The sheet metal of piece 12 preferably is resilient; thus, at least to a limited extent, walls 18 and 20 will press against the side walls 24 of package 22, and frictionally retain package 22 against movement relative to holder 10.

Wall 18 may have an opening 26 formed therein in any suitable manner, to provide means for exposing advertising matter, as, for instance, the advertising matter which may appear upon the outside face 38 of package 22. If desired, a suitably dimensioned card 32 bearing such matter may be positioned between package 22 and wall 18; then the advertising matter upon such

card will become apparent through opening 26. In order to retain such card 32, or other similar matter, edge portions 34 of wall 18 may be bent over and inwardly, to form a pair of guiding strips 36 defining receiving channels 38. Card 32 may be slid into channels 38 from top end 40. The pressure of walls 18 and 20, and of package 22, will serve to retain card 32 properly located.

In an alternate construction, as shown in Fig. 6, pairs of tines 42 may be struck inwardly out of wall 18 towards package 22, and so be bent as to extend towards each other. These tines may then serve for the reception of card 32.

A section 44 may be pressed outwardly from wall 20, and, at two ends 46, it is severed from the metal of wall 20. Section 44 is pressed out of the plane of wall 20 sufficiently to define a pair of substantially aligned openings or slits 48. Slits 48 are just long and wide enough so that the thickness of a flap 50 of a match packet 52 may be inserted therethrough. In Fig. 4, flap 50 has been threaded through slits 48; back wall 54 of packet 52 has been pulled through the slits, and is in contact with inner face 56 of section 44. The usual staple 57, which holds the match packet portions together, is brought to an end position by abutting against the lower edge of section 44. Matches 58 remain at the outside face 60 of section 44; flap 50 may then be turned down to cover matches 58, and be received in and held by upturned tab 62 of the packet, exposing striking material 64 in the usual manner.

As an alternate structure, tines 66 may be struck from wall 20, as shown in Fig. 6, to extend towards each other and to form receiving recesses for the passage of flap 50, and for retaining back wall 54.

As shown in Fig. 7, wall 20 may be pressed to form a section 68 extending from end edge 70 of wall 20 to a single slit 72. In such case, flap 50 would be inserted through slit 72, and then would be drawn so that it would turn over edge 70. In that case, back wall 54 would still be engaged against face 56, but flap 50 would be turned over edge 70, and then would be folded down into association with tab 62.

In a construction such as shown in Fig. 8, wall 20 has additional length which is bent into an apron 74, so that the apron extends substantially parallel to base 16. Apron 74 and base 16 are spaced apart a distance substantially equal to the standard height of package 22. In such case, the entire package, with the exception of two end faces 76, is encased by the holder. After package 22 has been opened and inserted into holder 16, and is held between base 16 and apron 74, access to cigarettes in the package is obtained by pushing against an end face 76, so that a portion 78 of package 22 which may have been torn open will be exposed beyond apron 74. Then, after a cigarette has been removed, the package may be returned to housed relationship merely by pushing against the end face 76 which is then extending beyond the holder. In this fashion, the package is protected against loss of cigarettes.

In the structure shown in Figs. 10 and 11, apron 74 has its free end edges 80 bent downwardly towards base 16, and then inwardly, to form a pair of flanges 82. These flanges then serve as means for retaining a moisture-retentive material 84. In the instance shown, plaster-of-Paris, before it hardened, had been smeared between flanges 82, and was left with a smooth surface 86. The extent of flanges 82 below apron

74 determined the depth of material 84. When the plaster-of-Paris hardened, it provided a boundary surface to bear against an end of the cigarette package. Material 84 may be moistened from time to time, and thus, simultaneously, will provide means for retaining moisture in juxtaposition to the cigarettes through the opened end of the cigarette package. Openings 87 may be formed in apron 74 to provide additional means for engagement of the plaster-of-Paris, to retain the solid against separation.

In using a device such as this, for example, a person, driving along, grasps the holder containing the cigarettes and matches in his hand. He can push the package beyond apron 74 with a single thumb, remove a cigarette, and then, with the rest of his fingers, push the package back into housed relationship. It is then a simple operation to open flap 50, tear off a match, and strike it upon material 64, without fussing around in his pockets to find the packet of matches, to open the packet, and to go through the various operations of striking the match. The matches and cigarettes are together at all times, and, furthermore, at least the ends of the cigarettes are at all times in a relatively humid atmosphere.

In the structure of Fig. 1, a U-shaped member 14, without an apron, is illustrated. An end edge 90 of wall 18 may be flanged over to provide a stop to prevent separation of card 32.

In the structure of Fig. 3, apron 74 has no moisture-retentive material, merely serving as an end cover for the opened cigarette package.

As shown in Fig. 2, base 16 may have a plurality of openings 94. Through these openings, suitable securing means may be projected; thus the entire holder may be secured to a pedestal as, for instance, an ash tray 96, so that the entire assembly may be positioned upon a table or like support.

Many other changes could be effected in the particular apparatus designed, and in the methods of operation set forth, and in the specific details thereof, without substantially departing from the invention defined in the claim, the specific description being merely of operating embodiments capable of illustrating certain principles of the invention.

What is claimed as new and useful is:

A retainer for a substantially rectangular package of predetermined dimensions one end of which is to be opened to provide access to the contents of the package, the retainer being formed from substantially resilient material, the retainer comprising a base providing a stand for the package, and a pair of walls extending upwardly from the edges of the base, the width of the base being sufficient to accommodate the width of the package so that the walls will engage snugly against a package positioned upon the base and between the walls, one of the walls having an apron at its end extending across the space between the walls and toward the end edge of the other wall, the apron having integrally formed downwardly directed projections, moisture-retentive material adhered to the inner face of the apron and retained by the projections to form a flat wall for the apron, the distance between the base and the flat wall being sufficient to hold the end faces of a package snugly and for the apron and the moisture-retentive material to provide a cover for the open end of the package when the package is completely housed in the retainer, the base, the end portion, the

moisture-retentive material, and the walls being associated so that the package may be moved sidewise under pressure applied positively to the free side faces of the package to present the opened package end for access to its contents.
